TOBACCO SMOKING APPLIANCE

Robert L. Spragins, Aberdeen Proving Grounds,
Md.

Application April 17, 1930, Serial No. 445,170

3 Claims. (Cl. 131—12)

The invention relates to smoking devices and more particularly has reference to smoking pipes and cigar and cigarette holders.

This application is a continuation in part of my copending applications Serial No. 310,596, filed October 5, 1928; Serial No. 405,162, filed November 6, 1929; and Serial No. 406,333, filed November 11, 1929.

Upon smoking there is formed within the bottom of a pipe bowl a dirty gummy mass, and as is well known, the stem becomes contaminated with a liquid condensed from the tobacco smoke. Frequently on drawing through the stem of the smoking device this liquid is injected into the smoker's mouth as well as particles of tobacco and saliva.

The difficulties encountered in smoking pipes is also present in the use of cigar and cigarette holders. While in the case of a holder the bowl is eliminated, a stem and mouthpiece through which the smoke is drawn into the smoker's mouth must be considered.

The major object of the invention is to devise a smoking device of simple design and inexpensive construction which ameliorates the inherent defects of smoking devices constructed in accordance with present practice.

Another important object of the invention is to provide means for preventing distasteful substances and particles of tobacco from being drawn into the mouth of the smoker while at the same time allowing the many pleasing properties of the smoke to remain unaltered.

With these and other objects in view, which 35 may be incident to my improvements, the invention consists in the parts and combinations to be hereinafter set forth and claimed, with the understanding that the several necessary elements comprising my invention may be varied in construction, proportions and arrangement without departing from the spirit and scope of the appended claims.

In order to make my invention more clearly understood, I have shown in the accompanying 45 drawing, means for carrying the same into practical effect without limiting the improvements in their useful applications to the particular construction, which for the purpose of explanation, have been made the subject of illustration.

50 In the drawing:

Figure 1 is a vertical sectional view along the longitudinal axis of a pipe constructed in accordance with my invention.

Figure 2 is a horizontal sectional view of the 55 pipe taken along the line 2—2 of Figure 1.

Figure 3 is a vertical sectional view taken along the line 3—3 of Figure 1, and shows in detail the neck of the smoking material receptacle.

Figure 4 is a vertical sectional view taken along the line 4—4 of Figure 1 showing the interior of 60 the intermediate member connecting the smoking material receptacle and the stem of the pipe.

Figure 5 is a vertical sectional view through the stem proper of the pipe taken along the line 5—5 of Figure 1.

Figure 6 is a vertical sectional view taken along the line 6—6 of Figure 1 and discloses a different view of the pipe stem and the mouthpiece associated therewith.

Figure 7 is a cross sectional view of the mouthpiece associated with the smoking device.

Fig. 8 is a vertical sectional view of a cigar holder constructed in accordance with my invention.

Throughout the drawing similar reference numerals refer to like parts in the different views. There is shown in Figure 1 a smoking device or appliance having a smoking material receptacle 1 provided with a neck 2 which has secured thereto an intermediate stem member 3, the opposite end of the latter being engaged by a stem 4. A mouthpiece generally designated by 5 is also shown associated with the smoking device, the end thereof being engaged by an end of the stem.

As it may be observed the intermediate stem member 3 is provided with reduced neck portions 6 and 7 which engage respectively the end of the neck 2 and the end of the stem 4. The diameters of the reduced portions are such that a tight fit between them and the parts just mentioned is 85 provided. A similar attaching feature is employed in securing the mouthpiece to the stem, the grip portion 8 thereof being likewise provided with a reduced neck portion 9 which engages an end of the stem. It will be appreciated that by 90 the construction just described the principal parts of the device may be readily detached from one another and afterwards assembled.

For the purpose of conducting smoke from the smoking material receptacle to the mouthpiece, the neck, intermediate stem member, stem and mouthpiece are provided with suitable smoke conducting passages. For example, the neck 2 is provided with a passageway 10 extending therethrough and communicating with the bowl 1. 100 This passageway, it should be noted, is near the top of the neck portion 2, as is clearly shown in both Figures 1 and 2. Adapted to be positioned within the passageway 10 is a conduit or smoke duct 11.

65

70

80

105

110

Besides the passageway 10 provided in the neck portion of the bowl, it may be observed that the lower part of the neck is formed with a compartment or chamber 12 which is unconnected from the bowl and from the passageway. The purpose of this compartment will hereinafter appear.

The reduced end 6 of the intermediate stem member 3 is provided with an enlarged opening 13 communicating with a compartment or chamber 14 formed in the intermediate stem member. It may be observed that the passageway having the smoke duct 11 positioned therein communicates with the opening 13. If desired, the ends of the passageway 10 may be formed with a flange 10' as shown, so that the ends of the passageway and smoke duct are flush with the face of the intermediate stem member. It will be appreciated, however, that other constructions for positioning the smoke duct so that it communicates with the passageway 13 and consequently the chamber 14 may be employed if desired without departing from the spirit of the invention.

The forward face of the reduced portion 6 is also provided with a passageway 15 which communicates with the compartment 12 formed in the bowl neck. As is shown a conduit 16 having a lip portion 17 is positioned in the passageway 15 so that the end of the conduit provided with the lip portion is within the compartment 12. It should be noted that by this construction, the purpose of which will hereinafter appear, the conduit 16 is positioned substantially in the center between the top and bottom of the chamber or compartment 12.

For the purpose of conducting the smoke from the compartment in the intermediate stem member, a passageway extends from the rearward end of this compartment through the intermediate member and has positioned therein a smoke duct 18. It should be noted that the longitudinal center lines of the smoke ducts 11 and 18 are out of alignment with each other as well as being out of alignment with the conduit 16. In this construction the smoke duct 11 is near the top of the chamber 14, the conduit 16 near the bottom of the chamber and the duct 18 intermediately placed between them. With reference to Figure 5 and Figure 2, it will be apparent that the smoke duct 18 is in the same horizontal plane as the longitudinal axis of the stem, being, as shown in Figure 5, to the left of the vertical axis of the stem.

As previously pointed out there is secured to the end of the intermediate member 3 most distant from the bore, a stem 4. This stem has formed therein a partition 19 which may either be integral therewith or secured therein in any desired manner. The partition is provided with a plurality of openings through one of which passes the smoke duct 18. By the provision of the partition it will be appreciated that the stem is divided into a forward compartment 20 and a rearward compartment 21, the duct 18 being of sufficient length to extend entirely through the forward compartment and to project for a considerable distance into the rearward compartment.

In the other opening of the partition, there is positioned a conduit 22 provided with a lip portion 23. The conduit 22 is substantially similar in all respects to the conduit 16 previously described, and provides a means of communication between the rearward compartment 21 and the forward compartment 20 of the stem. As in the case of the conduit 16 the end of the conduit 22 is provided with a lip 23 which extends

into the compartment or chamber of the stem nearest the pipe bowl. It should be observed that the conduit 22 provides means of communication between the compartments 21 and 20 which is entirely separated and unconnected from the smoke duct 18. As will presently appear any liquids in the compartment 21 will be conducted through the conduit 22 into the forward compartment 20, while smoke will not enter the forward compartment.

The stem 5 associated with the smoking device is provided with a grip portion 8 having the usual flanges formed upon the mouth end thereof. Through the grip portion 8 there extends a passageway having a uniform bore adapted to have inserted therein a tubular moisture absorbing member 24 which is maintained therein by frictional engagement with the walls of the grip piece. The moisture absorbing member is provided with a passageway through which the smoke is conducted from the smoke compartment 21 to the mouth of the smoker.

It may be observed that the moisture absorbing member 24 is of a length sufficient to extend entirely through its encasing grip piece and to project within the chamber 21 for a considerable distance. The passageway in the encasing grip piece 8 is so positioned that the moisture absorbing member when inserted therein, will be horizontally off center with respect to the longitudinal axis of the mouthpiece. This feature is clearly shown in Figure 2 and by such construction the end of the moisture absorbing member 24 is caused to overlap the end of the smoke duct 18. It should be noted that the moisture absorbing member 24 is entirely unconnected with the smoke duct 18 and moreover these two members overlap without touching each other.

While the construction disclosed has shown a horizontal type of overlap wherein the passageway in the mouthpiece for the moisture absorbing member is angularly disposed with respect to the longitudinal center line of the former, it will be appreciated that this passageway may be so formed as to be parallel to the longitudinal axis of the mouthpiece. Likewise a vertical type of overlap could be readily provided. In this instance either the vertical position of the smoke duct 18 or the vertical position of the moisture absorbing member 24 as shown in Figure 1, would be raised or lowered so that the ends of one of these members would be over the end of the other. With the vertical type of overlap it would be unnecessary to shift the horizontal position of the moisture absorbing member and the smoke duct 18 as both of them could lie in a vertical plane passing through the longitudinal axis of the smoking device.

As in the case of the smoke ducts and conduit which have their ends positioned within the chamber 14, it is to be noted that the smoke duct 18, moisture absorbing member 24 and conduit 22 within and communicating with the compartment 21 have their bores entirely out of coincidence with each other and furthermore are unconnected with each other.

Suitable materials are employed for the several elements of my pipe, the exact materials being apparent to those skilled in the art. For instance, the bowl may be made up from wood, clay or other suitable substances; smoke ducts 11 and 18 and conduits 16 and 22 may be made up of glass, hard rubber, phenolic condensation products or some similar substance; the stem members 3 and 4 may

be made up of phenolic condensation products or other equivalent material, as well as mouthpiece 8; and the moisture absorbing member 24 may be formed of a suitable porous and absorptive material such as wood, either seasoned maple or seasoned briar being preferable.

The bowl 1 is filled with tobacco or other smoking material which is ignited in the usual manner. Upon the smoker drawing upon the 10 mouthpiece smoke from the smoking material receptacle is drawn through the duct 11, forward compartment 14, smoke duct 18 into the rearward compartment 21 and finally through the moisture absorbing member 24 to the mouth of the smoker.

15 As the smoke passes through the conduit 11, vapor carried therein is condensed and a further condensation effect occurs within the compartment 14 after which the smoke is drawn through the conduit 18 and into the compartment 21, further condensation occurring within the last mentioned zones.

20 Liquids condensed in the conduit 11 drop into the compartment 15 and together with liquids condensed in the compartment itself and any liquids injected into the compartment 25 through conduit 18 are conducted into the drainage chamber 12 where they are entirely separated from the smoke. Similarly, liquids condensed in the smoke duct 18 and in the rearward compartment 21 as well as liquids injected into 30 the pipe through the moisture absorbing member, are collected at the bottom of the rearward compartment and are separated therefrom by being conducted through the conduit 22 and into the drainage unit 20.

35 It has been previously pointed out that the smoke ducts may be of glass, while the intermediate stem and the stem proper may be formed of a phenolic condensation product, or other similar material. It should be noted that these members are provided with relatively thick walls. While the preferred substances used in the formation of these members may be poor heat conductors, their heat absorbing capacity due to 45 their mass and the large surface or contact area which they present to the smoke will successfully effect the desired condensation of the vapor. Moreover, it will be appreciated that these substances possess relatively high specific heats and because of the mass of the members which they 50 form, there will be a substantial continual absorption of heat from the smoke during the whole time of a pipe smoking.

While a certain amount of condensation occurs within each of the smoke ducts, it will be understood that this amount is small when compared with that occurring in the condensation chamber 14 and in the condensation chamber 21. It should be noted that the smoke, when leaving the first condensation chamber 14 is subjected to a further condensation in the smoke duct 18, and a substantially complete condensation of the vapor carried thereby occurs within the condensation chamber 21.

Liquids contained in the compartment 14 are 65 prevented from entering the smoke duct 18 because of its elevation from the bottom or floor of the compartment. When the pipe is inclined so that the bowl is below and the mouthpiece is above the horizontal, liquids in this compartment will be conducted through the conduit 16 and into the drainage chamber 12 where they are 70 separated and substantially prevented from seeping back into the forward condensation chamber by reason of the position of the conduit 16 with respect to the floor of the drainage unit.

Liquids entering the compartment 14 through the smoke duct 18 will be similarly conducted to the drainage unit 12.

In operation any liquids condensed in the rearward compartment 21 or injected therein through the smoke conduit 18 will be conducted through the conduit 22 and into the drainage unit 20. It will be appreciated that because of the elevation of the conduit 22 above the floor of the stem proper, re-entry of these separated liquids into the condensation chamber 21 will be substantially prevented. Moreover, any liquids contained in the condensation chamber are prevented from reaching the smoke duct 18 and the moisture absorbing member 24 because of their elevations above the floor level of the stem.

As is well known, it frequently occurs that the smoker ejects saliva into the mouthpiece of the pipe. By reason of the nature of the absorbing member this will be substantially prevented. Should, however, any such liquids reach the inner end of the moisture absorbing member they would drop, by reason of gravity, to the bottom of the chamber 21 where they would be conducted in a manner similar to that described, into 100 the drainage unit 20 and there collected. It should be noted that the smoke conduit and the moisture absorbing member are out of coincidence with each other and that these two parts overlap. This construction besides allowing the 105 length of the pipe to be considerably shortened, positively prevents any liquid being drawn from the smoke duct into the mouth.

From an inspection of Figure 1 it may be observed that none of the smoke passes through the 110 drainage compartments as it is separated from the compartment 20 by reason of the enclosing duct 18, and entrance into the drainage compartment 12 is substantially prevented by the suction effect when the smoker draws through 115 the mouthpiece. As previously pointed out drainage from the condensation compartments 14 and 21 is collected and separated therefrom in the drainage units 12 and 20. Thus the liquids and filth formed and/or injected into the pipe are 120 entirely separated from the smoke so that the latter reaches the smoker's mouth in a dry condition free from contaminating substances.

The smoke in a substantially dry condition is 125 drawn from the rearward condensation chamber through the tubular moisture absorbing member and directly into the smoker's mouth. It has been pointed out that the moisture absorbing member is constructed of wood. While such a substance possesses a relatively high specific 130 heat, the mass of the member formed therewith is small, and moreover the other factor favorable to the occurrence of condensation, namely, a large contact area for the smoke within the moisture absorbing member is entirely lacking. This 135 is apparent upon considering the bore area of the moisture absorbing member itself. It will hence be well understood that substantially no condensation occurs therein. Condensation in the bore of the member 24 is further limited as 140 the smoke passing therethrough is in a substantially dry condition since by condensation, in the smoke ducts 11 and 18 and in the compartments 14 and 21, practically all of the condensable vapors carried thereby have been removed.

When it is desired to clean the pipe, the mouthpiece is removed from the stem by the exertion of a detaching force and the stem may be similarly disengaged from the intermediate stem member. Likewise the intermediate stem mem- 150

ber may be removed from its engagement with the neck of the smoking material receptacle.

The purpose of forming the opening 13 with a large periphery will now become apparent.

5 By this means the drying out of the passageway 13 and the chamber 14, in the intermediate stem member, is readily facilitated because of the large amount of air that may enter therein after the intermediate stem member has been 10 detached from the smoking device.

It will be apparent that my novel pipe stem construction may readily be adapted to a cigar holder as shown in Fig. 8, wherein the corresponding elements are identified by the same 15 numerals as the pipe stem described, except the stem is shown terminating with a recess 25 for receiving the end of a cigar, or if the recess is of less diameter, a cigarette.

It should be noted that the moisture absorbing 20 member of the mouthpiece is so constructed as to be removable from its encasing member or grip piece. The moisture absorbing member may thus be permitted to dry out while a new member is inserted in its place and used therefor.

25 The smoking device may be so constructed as to permit the smoke ducts and conduits within the stem, intermediate stem member and neck of the smoking material receptacle to be readily removed after these parts have been detached as 30 previously described. If desired, instead of positioning the smoke ducts within the smoking device so that they may be readily detached therefrom after the parts have been separated, they may be formed integral with the various parts 35 of the device.

The stem and intermediate stem members, as 40 previously mentioned are formed of phenolic condensation products, while the conduits and smoke ducts are of glass, both of which materials lend themselves to easy cleansing. In the assembly 45 of these parts it is apparent that the reverse operations are gone through. Obviously, in the construction shown, cleansing operations need be undertaken only at infrequent intervals, particu- larly when the moisture absorbing member is frequently changed.

While I have shown and described the preferred embodiment of my invention, I wish it to be understood that I do not confine myself to the 50

precise details of construction herein set forth, by way of illustration, as it is apparent that many changes and variations may be made therein, by those skilled in the art, without departing from the spirit of the invention, or exceeding the scope 80 of the appended claims.

I claim:

1. A smoking device comprising a smoking material receptacle having a neck portion, an intermediate stem member and a stem proper through which smoke passes to a mouthpiece, said stem being provided with a partition forming a condensation chamber and a drainage chamber therein communicating with each other, said intermediate stem member having a condensation 85 compartment formed therein and communicating with a drainage chamber formed in the neck portion of the smoking material receptacle, and a smoke duct extending through the drainage chamber of the stem and into the condensation 90 chamber thereof, said smoke duct adapted to conduct the smoke from the condensation chamber of the intermediate stem member.

2. A smoking device comprising a smoking material receptacle having a neck portion, an intermediate stem member, a mouthpiece, and a stem proper through which smoke passes to the mouthpiece, a passageway and a drainage chamber formed in said neck portion, a condensation compartment formed in the intermediate stem member 100 and communicating with the drainage compartment of the neck portion, a partition provided in said stem so as to form a condensation chamber and a drainage chamber, and a smoke duct communicating with the condensation 105 chamber of the intermediate stem member extending through said partition and into the condensation chamber of the stem, said smoke duct being unconnected from the mouthpiece and a moisture absorbing member, the end of the duct 110 overlapping an end of the moisture absorbing member encased by a grip portion of the mouthpiece.

3. A cigar holder comprising a plurality of sections providing a series of chambers, a conduit from one chamber through a second chamber to a third chamber, and a return conduit from the third to the second chamber.
